WILLIAM HENRY SMITH AND ALBERT STEWART WEBSTER, OF OTTAWA, ONTARIO, CANADA, ASSIGNEES TO AMERICAN BANK NOTE COMPANY, OF NEW YORK, N. Y., A CORPORATION OF NEW YORK.

METHOD OF AND APPARATUS FOR MAKING GUMMED PAPER.

Application filed January 26, 1928. Serial No. 83,781.

Our invention relates to a method of making gummed paper and an apparatus used in the practice of said method, and more particularly to a method and apparatus for the 5 production of non-curling gummed paper.

In the production of gummed paper, a solution of gum or other adhesive is applied to the paper, the removal or elimination of the solvent or other vehicle for the gum or 10 other adhesive being by a drying process, which causes the hardening or crystallization of the gum or other adhesive material. The contraction of the material of said body or its shrinkage during the hardening or 15 crystallization results in the development of stresses at one surface of the paper which causes the paper to curl.

While for some purposes the curling of 20 gummed paper is not objectionable, when a strip or web, or large sheets of such paper are to be printed upon, the paper, in order to permit its being properly fed in relation to the printing couple, and to permit the 25 making of a clean impression, should be flat, in order to secure quality in the printed product. In other words, non-curling paper is required in the better grades of printing when the impressions are made upon previously gummed paper.

30 In work of this kind, it has heretofore been the practice, particularly when printing on a paper web, to make the impression first and gum the opposite side of the sheet following the making of the impression.

35 While this practice obviates those difficulties during the making of an impression resulting from the use of curled gummed paper, in the subsequent cutting or perforating of such printed and gummed paper, difficulties 40 are encountered by reason of the tendency of the paper to curl, these difficulties resulting in a slowing down of such operations and the frequent spoilage of work.

It has heretofore been the practice in order 45 to avoid the above difficulties, to use certain materials such as red oil in the solution to weaken the bond between adjacent crystals of the body of the adhesive formed by the elimination of the vehicle from the adhesive, 50 and thus lessen the stresses due to the contraction of this material to an extent to materially lessen, if not to entirely avoid, distortion of the paper or its curling. It has

also been the practice to mechanically break down the bridge of crystals after the vehicle 55 has been removed from the adhesive, thus relieving the paper from the stresses and permitting it to flatten out.

The addition of oil to the adhesive tends to weaken its bonding properties when moisture is restored to the adhesive for making it "tacky", and the mechanical breakage of the crystalline structure of the dried adhesive not only involves a re-handling of the paper, but wastage of the adhesive during 60 the breaking operation. Furthermore a thicker coating of adhesive must be used to compensate for losses resulting from the flecking of the adhesive from the paper during 65 this breaking operation.

By the process of our invention, we are 70 enabled to produce a non-curling strip or web by a rapid and continuous operation while securing an effective substantially continuous coating of adhesive upon one surface thereof, which adhesive contains no oil or other moisture-repellant material which 75 will impair the bonding properties of the adhesive, or interfere with the quick absorption of moisture thereby when it is desired 80 to apply a piece of this gummed strip to any object.

By the process of our invention the vehicle 85 of the adhesive is removed from the body thereof under conditions which prevent the development of stresses due to the contraction of the material of the body of the adhesive, incidental to the hardening or crystallization of this material, thus avoiding 90 those conditions which result in the distortion or curling of the paper rather than using corrective ingredients in the adhesive, or destroying the conditions developing such stresses after the paper has once been distorted or curled. This permits the adhesive 95 to be applied in a thin coating to the paper, ensures the entire quantity of adhesive used 100 being retained in this coating, and permits the economical production of the paper from the standpoints of time and labor while securing a non-curling product. While the coating of adhesive is being applied to the paper, and the vehicle or solvent removed therefrom, the strip or web of paper is subjected 105 to a continuing longitudinal stress which assists in preventing the distortion or

curling thereof during the drying out process to which the adhesive coating is subjected. The time interval in the coating of the paper is very short, and the finished 5 gummed product is sufficiently flexible, and the gum thereon is sufficiently dry, to permit the paper to be readily wound upon a reel to facilitate its storage, its shipment or its use upon printing or other machines.

10 While we preferably apply the gum to the paper before the printing operation, and while it is in the form of a strip or web, it is obvious that the gum may be applied to the paper after the impression has been made 15 thereon or while the paper is in sheet form, although when applying the gum to sheets the results will not be as good as when applying it to a strip or web, since the longitudinal stresses in the sheet can not be advantageously secured and the evaporation 20 of the vehicle of the adhesive is more difficult and less rapid.

The invention consists primarily in the method of making gummed paper consisting in applying a solution containing adhesive material and a vehicle to the surface of paper, subjecting the same to a low temperature and then to a relatively higher temperature, whereby the vehicle will be 25 removed from the surface of the solution inwardly thereof progressively to cause a progressive crystallization of the adhesive material and the readjustment of the adhesive material during its crystallization and 30 avoiding those stresses resulting in curling of the paper, and in an apparatus for carrying on said process; all as hereinafter set forth and described, and more particularly pointed out in the claims hereto appended.

35 In the accompanying drawing, we have illustrated an apparatus particularly adapted for use in the rapid gumming of a paper strip or web.

In the production of gummed paper by 40 the method of our invention, we apply to one surface of the paper a solution containing an adhesive material and a vehicle, this solution being spread in a thin film throughout that portion of the paper which is to be gummed. The adhesive material used in 45 this solution may vary widely as may the solvent constituting the vehicle, our invention not depending in any way upon the particular material or solvent since with all 50 adhesives the hardening thereof results from a drying out process, or the elimination, as by evaporation, of the solvent or vehicle. This hardening action results in a crystallization of the adhesive material and the 55 method of our invention resides in so controlling the speed of elimination, or evaporation, of the vehicle as to secure the complete hardening thereof without development of stresses resulting from the contraction of 60 the adhesive as a mass, or its shrinkage as a

mass, to an extent to cause curling of the paper, due to the paper, particularly when dry, having substantially no shrinkage or a lower shrinkage than the adhesive.

After the thin film of adhesive solution 70 is applied to the paper, it is subjected to a low temperature as by passing it through a zone maintained at the desired temperature which may be ordinary factory temperatures or about 70 to 90° F. Any particular temperature in this zone is not required so long as it is sufficiently low to cause a slow evaporation of the vehicle or solvent and limit this action to adjacent the exposed 75 surface of the film of adhesive solution.

Immediately following the subjection of the coated paper to this low temperature, it is subjected to a relatively higher temperature to cause the elimination or evaporation of the vehicle, or solvent, within the 80 surface of the film of adhesive solution, the paper finally being subjected to a still higher temperature in order to ensure the completion of the elimination, or evaporation, of the solvent throughout the entire mass of the 85 adhesive and the complete drying of the exposed surface of the adhesive.

The best results can be secured by holding the paper substantially flat or taut while it is being subjected to these different temperatures, and subjecting it to a bending action before it is subjected to the higher temperature, or following hardening, or partial hardening, by crystallization, of the adhesive material adjacent the surface of the film and before the material between this surface and the paper has been thus hardened, or at least hardened to an extent to have attained its maximum shrinkage.

It is preferable to maintain a continuing circulation of air in the low temperature zone and of heated air in the high temperature zone, in order to secure a continuing substantially uniform evaporation of the vehicle or solvent.

When bending the paper, it is subjected to stresses which while not great are sufficient to break or weaken the bond between adjacent crystals of the adhesive material and thus cause a readjustment of the solution while it is still in a viscous or semi-plastic state, and a readjustment of this material of the solution in a manner to compensate for its shrinkage, or contraction, as a mass and prevent the distortion or curling of the paper.

The portion of the adhesive solution which will be last to harden or crystallize will be that which is adhered, or anchored, to the paper itself so that the subsequent hardening of this portion of the adhesive by reason of the more or less separated portions thereof entering the fibers of the paper, will have no effect of distorting the paper.

While the method of our invention in-

volves the temperature stages above referred to, the time intervals are very short, thus permitting the rapid production of gummed paper particularly when the same is produced in strip or web form, which lends itself particularly to the efficient practice of the method. We have found in actual practice that highly satisfactory non-curling paper may be produced in about one-half a minute, the paper requiring about one-quarter of a minute in the lower temperature zone and about the same length of time in the higher temperature zone, and being subjected to the final high temperature for between three to five seconds. These time intervals, however, are not inflexible, and will vary according to the adhesive material in the solution and the quantity of the vehicle or solvent.

20 Satisfactory results can be secured with a temperature in the heated zone ranging from about 125° to 200°, the higher temperature being utilized for the final stage, at which point the adhesives will have had substantially all of the vehicle or solvent removed, so that the higher temperatures used will cause no reactions which will destroy the adhesive properties of the gummed surface when moisture is applied thereto, when it is desired to use the article made from the paper. The lower range of these higher temperatures represents the normal drop in the temperature of the air circulating in the heated zone, the first heated zone being characterized by the presence of a graduated temperature which becomes progressively higher with a lowering of the quantity of the vehicle or solvent in the adhesive, or with the progressive elimination or evaporation of such moisture.

So far as we have been able to determine, the practice of the method of our invention is characterized by the following conditions.

As the paper with its coating film of adhesive solution is passing through the low temperature zone, the vehicle or solvent of the portion of the adhesive adjacent the exposed surface thereof will rapidly be eliminated or evaporated, thus causing a hardening, or partial hardening of the solution superficially of this film. This action will be accompanied by shrinkage of the adhesive material of this portion of the solution, but this shrinkage will be in relation to the contiguous portions of the solution, and hence will merely cause a readjustment of these portions of the solution or of the adhesive material without subjecting the paper to any of the stresses resulting from this contraction or shrinkage. This action will go on progressively through the thickness of the film so that by the time the treatment in the low temperature zone is completed, the shrinkage or contraction of the material of the adhesive solution will have progressed to

a point where any subsequent shrinkage will be so small as to have no effect in imparting a curl to the paper.

At the conclusion of this stage the elimination, or evaporation, of the vehicle or solvent will not have occurred as to the whole mass of the adhesive solution, and the continuing escape of said vehicle or solvent will tend to keep the entire mass in a viscous condition. Hence a bending of the paper away from the coating film, accompanied by pressure resulting from stresses applied through the paper against the object over which the paper is bent, will have the effect of causing the readjustment of different parts of the adhesive with relation to each other, in a manner to counteract any shrinkage or contraction which has occurred from the partial or complete hardening of some of the material. Consequently the subsequent rapid elimination, or evaporation, of the remaining vehicle or solvent will be accompanied by so little contraction or shrinkage as to have no effect of curling the paper; particularly as during this stage, the portion of the adhesive solution which is subjected to contraction or shrinkage will be between that portion thereof superficially of the film and adjacent thereto and the paper, and will meet with resistance from the paper, and also from the previously hardened or partially hardened portion of the film. The condition of the adhesive in passing from the low to the higher temperature stage is also such that the bending action accompanied by pressure will not cause crackage or flecking at the surface of the adhesive, and may even be accompanied by a stretching or attenuation of partially hardened portions of the film, or the separation of adjacent particles in a manner to prevent the development of those stresses which would curl the paper.

In passing through the zone of higher temperature, the vehicle or solvent between the superficial portion of the film of adhesive and the portion thereof which has been hardened or partially hardened, will be rapidly expelled from the adhesive, this portion of the coating, however, having undoubtedly already been subjected to a certain degree of contraction or shrinkage, and having been readjusted with relation to the paper and to the hardened or partially hardened material, superficially of the film, and adjacent thereto. In fact, when passing through this stage, the drying out of the adhesive solution has progressed to a point where subsequent elimination of the remaining vehicle or solvent will not result in such contraction or shrinkage of the material of the coating as to apply any stresses to the paper.

The portion of the adhesive in direct contact with, and anchored to the surface fibers

of the paper, with the elimination, either complete or partial, of the vehicle or solvent therefrom, will have the more or less segregated portions thereof contract or shrink in relation to the paper, and away from each other so as not to be so bonded to adjoining crystals of the adhesive as to have any effect in developing stresses tending to distort or curl the paper.

Throughout, the method is characterized by the hardening or partial hardening of a portion of the adhesive material resulting from the elimination or evaporation of the vehicle or solvent therefor, accompanied by contraction or shrinkage of this portion of the adhesive, this contraction or shrinkage being with relation to portions of the adhesive which are still in a viscous or semi-plastic form so as not to transmit any stresses to the paper which would result in the curling action. By thus avoiding the effects of such contraction or shrinkage, the thickness of the film of adhesive solution may be restricted to secure the desired thickness of the dried gum or other adhesive material upon the finished product, there being no losses due to the flecking of particles of the material as when breaking down a completely formed bridge of the crystals. Furthermore, there will be no cracking of the dried adhesive.

The product is gummed paper having no appreciable tendency to curl, and having a thin continuous film of dried adhesive thereon.

The method is not only economical because of the possibility of increasing the cheapness of the ingredients of the solution, and a reduction in the quantity of the adhesive used to coat the paper, but also by reason of the high speed at which paper, particularly in strip or web form, may be coated with the gum and the fact that the process may be carried on by means of an apparatus requiring little or no attention from the operator.

An apparatus suitable for use in the practice of said method or art is shown in the accompanying drawing. As shown, this apparatus embodies a frame 1 provided with bearings for a reel 2 for a roll of paper to be coated. Adjacent said bearings is a fountain 3 adapted to receive a supply of the adhesive, this fountain having associated therewith a roll 4 suitably surfaced to pick up adhesive from the fountain and apply it to paper fed with relation thereto. Co-operating with the fountain roll 4 is a feed roll 5, a tension roll 6 being positioned between this feed roll and the supply reel of the paper supply roll.

Closely adjacent the adhesive solution applying mechanism, is a vertically extending housing or stack 7 open toward the bottom thereof so as to permit air to circulate freely through said housing or stack.

The top of the stack is provided with a hood 8 having a vent pipe communicating with atmosphere to facilitate the aforementioned circulation of air while at the same time removing any fumes resulting from the elimination, or evaporation, of the vehicle or solvent from the adhesive material.

Adjacent the bottom of the stack is a turning roller 9 about which the paper strip or web passes after leaving the fountain roll 4 and feeding roll 5, and is directed upwardly within the housing or stack 7. Adjacent the top of the stack is a guide roller 10 in substantial alignment with the turning roller 9, and a second roller 11 which, for convenience of expression, will be termed a breaker roller, about which the paper strip or web passes and changes its course from an upward to a downward run.

Mounted in the frame 1 is a rewind reel 12 co-operating with which are squeeze rollers 13 and 14 by which the paper strip or web is frictionally fed through the machine and rewound upon the reel 12. One of these rollers as 13 is driven from any source of power as the motor 15. Below the stack and in substantially vertical alignment with the roller 11 is a turning roller 16, and between this roller 16 and the squeeze roller 13 are suitable guiding and tensioning rollers 17, 18 and 19.

Mounted upon the frame 1 below the stack 7 is a roller 20 and adjacent the top of the stack is a second roller 21 about which an endless traveler belt 22 of substantially the same width as the housing or stack, passes. The roller 21 is preferably of smaller diameter than the roller 20. The belt 22 divides the housing or stack 7 into two passages or conduits, which for all practical purposes are unconnected except adjacent the top of the housing or stack. One of these passages, indicated at 23, permits the circulation of air at normal factory temperatures therethrough, so that it may properly be termed a cold air conduit. The other of these passages, indicated at 24, has heated air delivered thereto adjacent the bottom thereof from any desired source of heat, and hence may appropriately be termed a hot air conduit. In the upward run of the paper or web in the housing or stack 7, it passes through the cold air conduit 23 and in its downward run, it passes through the hot air conduit 24 and toward the point where the heated air is delivered to the stack.

In the form of the invention shown, the source for the heated air is an electrical resistance device 25 supported from the frame 1 of the machine adjacent the bottom of the housing or stack 7, and also adjacent the roller 20, so that air in passing between said housing and said source of heat will attain the temperature required in the practice of the method of our invention.

5 The feed roll 5 and the roller 20 are driven in any desired manner so as to secure a feeding of the paper strip or web from the supply roll, with substantially the same speed as that of the travel of the belt 22. The speed of the roller 13 is also such as to ensure the travel of the paper at substantially the same speed as that of said belt 22, while keeping the strip or web taut.

10 As shown in the drawing, the roller 5 is driven from an electric motor 26, and is connected by a chain and pulley mechanism 27 with the roller 20 so as to secure the desired relative speeds of said rollers 5 and 20 to secure the above results. The paper strip or web is indicated at 28.

15 In an apparatus as herein described, the paper strip or web 28 is led from the roll upon the reel 2 under the tension roller 6, between the rollers 4 and 5, about the turning roller 9, over the guide roller 10, about the breaking roller 11, downwardly toward and about the rollers 16, 17, 18 and 19, between the squeeze rollers 13 and 14, and 20 upon the rewind reel 12. When the paper is thus threaded through the machine, it will be noted that the upward reach thereof is within the cold air conduit 23 of the housing or stack 7, and is positioned away from the upward reach of the belt 22, and that there is a progressively increasing capacity of this conduit toward the top thereof by reason of the inclination of the belt 22; and that the downward reach of the paper strip or web is within the hot air conduit 24. Toward the end of this downward reach, the gummed surface of the paper is presented towards the electrical resistance device 25.

25 With this construction, as the paper strip or web 28 passes between the rollers 4 and 5, one surface thereof has a thin film of adhesive solution from the fountain 3 applied thereto, the turning roller 9 having a spreading action upon this film, although its main purpose is to change the direction of travel of the paper or web to an upward course through the cold air conduit 23. As the paper passes through this cold air conduit, the gummed surface thereof is presented away from the belt 22 where it will be subjected to the action of the air flowing upwardly through the conduit 23. The un-gummed surface of the paper will be held away from the belt 22 by the upper guide roller 10. This upward reach of the roller is approximately 30 feet long, although this length is stated as merely one at which satisfactory results have been attained, and not as being essential.

30 After passing the guide roller 10, the strip or web 28 passes about the roller 11, where it receives a fairly sharp bend, and is subjected to pressure resulting from the drag upon the strip by the squeeze rollers 13 and 14, and passes downwardly through

the hot air conduit 24. It will be observed that during the part of this travel adjacent the top of the housing or stack 7, the hot air will have lost some of its heat through radiation, and that hence there will be a 70 gradually increasing temperature from this point to a point adjacent the heater 25 where the temperature will be at its highest. Hence during the downward travel of the paper strip or web 28 through the hot air 75 conduit, it will be subjected to a progressively higher temperature, and will, while passing the heater 25, be subjected to a substantially uniform high temperature.

80 While the strip or web 28 is passing upwardly through the conduit 23, the cold air will act superficially of the film of adhesive solution upon the paper strip or web, the rapid circulation of cold air ensuring a 85 continuous supply of fresh air and a change of this air with sufficient rapidity to carry off the vehicle or solvent for the adhesive material as it evaporates from the solution. This action will be gradual, and will have the effect of limiting the initial 90 hardening action to adjacent the surface of the film of the solution.

95 In passing about the breaking roller 11, the sharp bend of the paper strip or web, and the pressure resulting from the drag thereon from the squeeze rollers 13 and 14, will assist in so readjusting different portions of the adhesive solution, both as to the hardened or partially hardened and the un-hardened portions thereof, to compensate 100 for any shrinkage or contraction of the portion thereof which has been hardened or partially hardened.

105 During the downward run of the paper strip or web 28 through the hot air conduit 24, the coated surface of the paper will be presented away from the belt 22 and the higher temperature of the air circulating through this conduit will cause a rapid elimination, or evaporation, of the vehicle or 110 solvent remaining in the film of the solution. Throughout at least a portion of the travel of the paper strip or web through this conduit 24, the surface of the adhesive film will be tacky, but the passage thereof adjacent 115 the heater 25 will have the effect of a final rapid drying action upon this coating, so that after the strip or web 28 leaves its proximity to the heater, the adhesive will be sufficiently dry and hard to permit it to 120 pass the various guide and tensioning rollers 16, 17, 18 and 19 and the squeeze rollers 13 and 14, and be rewound upon the reel 12 without any likelihood of the gummed surface of the paper strip or web adhering to 125 these rollers or to the strip previously wound upon said reel.

130 We have found an apparatus as herein described, to give highly satisfactory results, and to produce a gummed paper which

has no tendency to curl, so that gummed paper may be withdrawn from the roll upon said reel and passed through a printing machine, and have a clean sharp impression applied to every portion thereof.

We have secured highly efficient results with a speed of travel of the paper of about 100' per minute, which results in a completion of the gumming operation as to 10 every portion of the paper, in about one-half minute.

It is not our intention to limit the invention to the precise details of construction shown in the drawing, it being apparent that 15 such may be varied without departing from the spirit and scope of the invention.

Having described the invention, what we claim as new and desire to have protected by Letters Patent, is:—

20 1. The herein described method of making gummed paper consisting in applying a solution containing adhesive material and a vehicle to one face only of paper, subjecting the same to a low temperature and then 25 to a relatively higher temperature, whereby the vehicle will be removed from the surface of the solution inwardly thereof progressively to cause a progressive crystallization of the adhesive material and the re- 30 adjustment of the adhesive material during its crystallization and avoiding those stresses resulting in curling of the paper.

2. The herein described method of making gummed paper consisting in applying a 35 solution containing adhesive material and a vehicle to one face only of paper, subjecting the same to a low temperature, then to a relatively higher temperature, whereby the vehicle will be removed from the 40 surface of the solution inwardly thereof progressively to cause a progressive crystallization of the adhesive material and the re-adjustment of the adhesive material during its crystallization and avoiding those 45 stresses resulting in curling of the paper, and thereafter subjecting the same for a short interval to a relatively higher temperature to ensure a thorough drying out of the adhesive at the surface thereof.

50 3. The herein described method of making gummed paper consisting in applying a solution containing adhesive material and a vehicle to one face only of the paper, circu- 55 lating air at a low temperature adjacent said surface, and thereafter circulating air at a relatively higher temperature adjacent said surface, whereby the vehicle will be removed from the surface of the solution inwardly thereof progressively to cause a pro- 60 gressive crystallization of the adhesive material and the readjustment of the adhesive material during its crystallization and avoiding those stresses resulting in curling of the paper.

65 4. The herein described method of mak-

ing gummed paper consisting in applying a solution containing adhesive material and a vehicle to one face only of the paper, circu- 70 lating air at a low temperature adjacent said surface, thereafter circulating air at a relatively higher temperature adjacent said surface, whereby the vehicle will be removed from the surface of the solution inwardly thereof progressively to cause a progressive crystallization of the adhesive material and the adjustment of the adhesive material 75 during its crystallization and avoiding those stresses resulting in curling of the paper, and thereafter subjecting the same for a short interval to a relatively higher temperature to ensure a thorough drying out of the adhesive at the surface thereof.

5. The herein described method of making gummed paper consisting in applying and spreading a solution containing adhesive material and a vehicle to one face only of a strip or web of paper, passing said strip or web upwardly while subjecting it to circu- 80 lating air at low temperature, and thereafter passing said web downwardly while subjecting it to an upward circulating air at a relatively higher temperature, whereby the vehicle will be removed from the surface of the solution inwardly thereof pro- 85 gressively to cause a progressive crystallization of the adhesive material and the re-adjustment of the adhesive material during its crystallization and avoiding those 90 stresses resulting in curling of the paper.

6. The herein described method of making gummed paper consisting in applying and spreading a solution containing adhesive material and a vehicle to one face only of a strip or web of paper, passing said strip or web upwardly while subjecting it to circu- 100 lating air at low temperature, thereafter passing said web downwardly while subjecting it to upwardly circulating air at a relatively higher temperature, whereby the vehicle will be removed from the surface of the solution inwardly thereof pro- 105 gressively to cause a progressive crystallization of the adhesive material and the re-adjustment of the adhesive material during its crystallization and avoiding those 110 stresses resulting in curling of the paper.

7. The herein described method of making gummed paper consisting in applying a solution containing adhesive material and a vehicle to one face only of paper, subjecting the same to a low temperature, giving a sharp bend to the paper in the direction away from the surface having the adhesive thereon and simultaneously applying stresses to the paper on opposite sides of the point where it is bent, and thereafter to a rela- 120

tively higher temperature, whereby the vehicle will be removed from the surface of the solution inwardly thereof progressively to cause a progressive crystallization of the adhesive material and the readjustment of the adhesive material during its crystallization and avoiding those stresses resulting in curling of the paper.

8. The herein described method of making gummed paper consisting in applying and spreading a solution containing adhesive material and a vehicle to one face only of a strip or web of paper, passing said strip or web upwardly while subjecting it to circulating air at low temperature, giving a sharp bend to the paper in the direction away from the surface having the adhesive thereon and simultaneously applying stresses to the paper on opposite sides of the point where it is bent, and thereafter passing said web downwardly while subjecting it to upwardly circulating air at a relatively higher temperature, whereby the vehicle will be removed from the surface of the solution inwardly thereof progressively to cause a progressive crystallization of the adhesive material and the readjustment of the adhesive material during its crystallization and avoiding those stresses resulting in curling of the paper.

9. The herein described method of making gummed paper consisting in applying a solution containing adhesive material and a vehicle to one face only of paper, subjecting the same to a low temperature, giving a sharp bend to the paper in the direction away from the surface having the adhesive thereon and simultaneously applying stresses to the paper on opposite sides of the point where it is bent, thereafter subjecting it to a relatively higher temperature, whereby the vehicle will be removed from the surface of the solution inwardly thereof progressively to cause a progressive crystallization of the adhesive material and the readjustment of the adhesive material during its crystallization and avoiding those stresses resulting in curling of the paper, and thereafter subjecting the same for a short interval to a relatively higher temperature to ensure a thorough drying out of the adhesive at the surface thereof.

10. The herein described method of making gummed paper consisting in applying and spreading a solution containing adhesive material and a vehicle to one face only of a strip or web of paper, passing said strip or web upwardly while subjecting it to circulating air at low temperature, giving a sharp bend to the paper in the direction away from the surface having the adhesive thereon and simultaneously applying stresses to the paper on opposite sides of the point where it is bent, thereafter passing said web downwardly while subjecting it to

upwardly circulating air at a relatively higher temperature, whereby the vehicle will be removed from the surface of the solution inwardly thereof progressively to cause a progressive crystallization of the adhesive material and the readjustment of the adhesive material during its crystallization and avoiding those stresses resulting in curling of the paper, and thereafter subjecting the same for a short interval to a relatively higher temperature to ensure a thorough drying out of the adhesive at the surface thereof.

11. The herein described method of making gummed paper consisting in applying a solution containing adhesive material and a vehicle to one face only of paper, subjecting the same to a low temperature and then to a relatively higher, and a gradually increasing, temperature, whereby the vehicle will be removed from the surface of the solution inwardly thereof progressively to cause a progressive crystallization of the adhesive material and the readjustment of the adhesive material during its crystallization and avoiding those stresses resulting in curling of the paper.

12. The herein described method of making gummed paper consisting in applying a solution containing adhesive material and a vehicle to one face only of the paper, circulating air at a low temperature adjacent said surface, thereafter circulating air at a relatively higher, and a gradually increasing, temperature adjacent said surface, whereby the vehicle will be removed from the surface of the solution inwardly thereof progressively to cause a progressive crystallization of the adhesive material and the readjustment of the adhesive material during its crystallization and avoiding those stresses resulting in curling of the paper, and thereafter subjecting the same for a short interval to a relatively higher temperature to ensure a thorough drying out of the adhesive at the surface thereof.

13. The herein described method of making gummed paper consisting in applying and spreading a solution containing adhesive material and a vehicle to one face only of a strip or web of paper, passing said strip or web upwardly while subjecting it to circulating air at low temperature, thereafter passing said web downwardly while subjecting it to upwardly circulating air at a relatively higher, and a gradually increasing, temperature, whereby the vehicle will be removed from the surface of the solution inwardly thereof progressively to cause a progressive crystallization of the adhesive material and the readjustment of the adhesive material during its crystallization and avoiding those stresses resulting in curling of the paper, and thereafter subjecting the same for a short interval to a relatively higher

temperature to ensure a thorough drying out of the adhesive at the surface thereof.

14. The herein described method of making gummed paper consisting in applying a solution containing adhesive material and a vehicle to one face only of paper, subjecting the same to a low temperature, giving a sharp bend to the paper in the direction away from the surface having the adhesive thereon and simultaneously applying stresses to the paper on opposite sides of the point where it is bent, thereafter subjecting it to a relatively higher, and a gradually increasing, temperature, whereby the vehicle will be removed from the surface of the solution inwardly thereof progressively to cause a progressive crystallization of the adhesive material and the readjustment of the adhesive material during its crystallization and avoiding those stresses resulting in curling of the paper, and thereafter subjecting the same for a short interval to a relatively higher temperature to ensure a thorough drying out of the adhesive at the surface thereof.

15. An apparatus for making gummed paper embodying therein means supporting a roll of paper to be coated, a fountain for a solution of adhesive material, a fountain roll, a feeding roll co-operating therewith, and adapted to apply the adhesive to one surface only of the paper to be coated, a stack open at the bottom and at the top thereof, means dividing said stack into two substantially vertical passages, means for guiding the coated paper strip or web in an upward run through one of said passages, and in a downward run through the other of said passages, means whereby the temperature of the air passing through the last named of said passages is heated, a rewind reel, guiding means intermediate said last named means and said rewind reel, and means drawing the paper from said supply reel and winding it upon said rewind reel, whereby said paper is subjected to continuous longitudinal stresses.

16. An apparatus for making gummed paper embodying therein means supporting a roll of paper to be coated, a fountain for a solution of adhesive material, a fountain roll, a feeding roll co-operating therewith and adapted to apply the adhesive to one surface only of the paper to be coated, a stack open at the bottom and at the top thereof, means dividing said stack into two substantially vertical passages, means for guiding the coated paper strip or web in an upward run through one of said passages, a breaker roller adjacent the top of the means dividing said stack, about which the paper strip or web passes into a downward run through the other of said passages, means whereby the temperature of the air passing through the last named of said pas-

sages is heated, a rewind reel, guiding means intermediate said last named means and said rewind reel, and means drawing the paper from said supply reel and winding it upon said rewind reel, whereby said paper is subjected to continuous longitudinal stresses. 70

17. An apparatus for making gummed paper embodying therein means supporting a roll of paper to be coated, a fountain for a solution of adhesive material, a fountain roll, a feeding roll co-operating therewith and adapted to apply the adhesive to one surface only of the paper to be coated, a stack open at the bottom and at the top thereof, rollers adjacent the top and the bottom of said stack, an endless belt passing about said rollers whereby said stack is divided into two substantially vertical passages, means for guiding the coated paper strip or web in an upward run through one of said passages, and in a downward run through the other of said passages, means whereby the temperature of the air passing through the last named of said passages is heated, a rewind reel, guiding means intermediate said last named means and said rewind reel, and means drawing the paper from said supply reel and winding it upon said rewind reel, whereby said paper is subjected to continuous longitudinal stresses. 90

18. An apparatus for making gummed paper embodying therein means supporting a roll of paper to be coated, a fountain for a solution of adhesive material, a fountain roll, a feeding roll co-operating therewith, a stack open at the bottom and at the top thereof, rollers adjacent the top and the bottom of said stack, an endless belt passing about said rollers whereby said stack is divided into two substantially vertical passages, means for guiding the coated paper strip or web in an upward run through one of said passages, a breaker roller adjacent the upper of said rollers about which said belt passes, about which the paper strip or web passes into a downward run through the other of said passages, means whereby the temperature of the air passing through the last named of said passages is heated, a rewind reel, guiding means intermediate said last named means and said rewind reel, and means drawing the paper from said supply reel and winding it upon said rewind reel, whereby said paper is subjected to continuous longitudinal stresses. 105

19. An apparatus for making gummed paper embodying therein means supporting a roll of paper to be coated, a fountain for a solution of adhesive material, a fountain roll, a feeding roll co-operating therewith, a stack open at the bottom and at the top thereof, rollers adjacent the top and the bottom of said stack an endless belt passing about said roller whereby said stack is divided into two substantially vertical pas- 125

sages, means for guiding the coated paper strip or web in an upward run through one of said passages, a breaker roller adjacent the upper of said rollers about which said belt passes, about which the paper strip or web passes into a downward run through the other of said passages, means whereby the temperature of the air passing through the last named of said passages is heated, a 10 rewind reel, guiding means intermediate said last named means and said rewind reel, squeeze rollers engaging the web adjacent said rewind reel and acting upon the web wound upon said reel, whereby said

paper is drawn through said stack and subjected to continuous longitudinal stresses, and means whereby said feeding roll, and said fountain roll, and said squeeze rollers are respectively rotated at the same peripheral speed and said belt is driven at substantially the same speed as that of the 15 paper strip or web.

In witness whereof we have hereunto affixed our signatures this 19th day of January, 1926.

WILLIAM HENRY SMITH.
ALBERT STEWART WEBSTER.
